UNITED STATES PATENT OFFICE.

ROLLAND P. SMITH, BERL I. SMITH, AND LEONARD M. LASLEY, OF PORTLAND,
OREGON.

SALES-SLIP TABLET.

1,178,685.

Specification of Letters Patent. Patented Apr. 11, 1916.

Application filed May 8, 1915. Serial No. 26,869.

To all whom it may concern:

Be it known that we, ROLLAND P. SMITH, BERL I. SMITH, and LEONARD M. LASLEY, citizens of the United States of America, residing at Portland, in the county of Multnomah and State of Oregon, have invented certain new and useful Improvements in Sales-Slip Tablets, of which the following is a specification, reference being had thereto in to the accompanying drawing.

This invention relates to a sales slip tablet and has for its object the production of a simple and efficient holder whereby the sales slips may be conveniently and efficiently supported to permit the salesman to easily record the sales upon the slip and retain the desired copies thereof for his own record.

Another object of this invention is the production of a simple and efficient casing for supporting the paper roll in such a manner as to permit the several slips, that is to say the original and copies thereof, to be efficiently recorded by the party using the holder.

Other objects and advantages of the present invention will appear throughout the following specification and claims.

In the accompanying drawing:—Figure 1 is a perspective view of the holder. Fig. 2 is a perspective view of the casing of the holder, several parts thereof being shown in an open position. Fig. 3 is a perspective view of the main casing of the holder showing the upper portion swung backwardly from the roller supporting portion thereof. Fig. 4 is a central longitudinal section through the casing. Fig. 5 is a top plan view of the connector for holding or supporting the holder upon the belt or garment of the clerk or user of the device. Fig. 6 is an enlarged section showing the manner of holding the carbon copies between the several layers of retaining sheets.

By referring to the drawing it will be seen that 1 designates the main casing, which main casing is provided at one end with a pair of spaced ears 2 having sockets 3 formed therein. A roller 4 is detachably secured in the sockets 3 and is adapted to support a paper roll 5 clearly illustrated in Fig. 4 of the drawing. A cover 6 is hingedly secured to the body 1 as clearly illustrated in Fig. 3 and is provided with a centrally located aperture 7 to permit the recording or recorded sheets 8' to be readily viewed

through the cover 6. This cover 6 is provided with a projecting edge 8 which is sharpened as indicated at 9 to permit the several layers of paper 10 to be torn off at 60 a desired point such as illustrated in Fig. 1 of the drawing. The main body 1 is provided upon the bottom thereof with a hinged door 11, which hinged door is normally held in a closed position by means of a coil 65 spring 12, which coil spring is carried by the side walls 13 of the body 1 and engages the inner face of the door 11 for normally holding the same in a closed position such as illustrated in Fig. 4. It will, therefore, 70 be seen that a compartment has been provided within the body 1 to retain or hold the carbon copies of the sales slips which have been written by the sales clerk. The body 1 is provided upon each side with a 75 latch member 14, and each latch member 14 is provided with a projecting knob 15 extending beyond the sides of the body 1 and is also provided with a beveled tongue 16 adapted to fit in the notches 17 formed 80 in the side flanges 18 of the cover 6 and normally hold the cover 6 in a set or closed position upon the body 1. It should be understood that the latches 14 are preferably formed of spring metal and are fixedly secured at their inner ends at 19 as illustrated 85 in Figs. 2 and 4 of the drawing.

A carbon sheet holder 20 is supported upon the ears 2 of the body 1 in any suitable or desired manner, and comprises a plurality of longitudinally extending rods to which the carbon sheets 21 are adapted to be secured.

The cover 6 is provided with a plurality of superimposed overhanging flanges 22, 95 which overhanging flanges are adapted to constitute a retaining means for receiving the tally sheet 23 which is adapted to contain a brief record of all of the sales made by the sales clerk. It should be understood 100 that these sheets 23 may be readily placed under the flanges 22 and in this manner be firmly held in an efficient position.

Upon carefully considering Fig. 2 it will be seen that the body 1 comprises a face 105 29, a pair of side flanges 13, 13', and an end flange 13'' and a compartment 6' for holding a roll of paper, the door 11 constituting a closure for the bottom of the body 1 under normal conditions, and being closed as 110 above stated by means of a spring 12.

A yoke 24 is secured to the body 1 by

having its inwardly bent ends 25 fitting in the apertures 26 formed in the body 1. A link 27 is secured to the yoke 24, and this link is in turn connected to the hook 28 as 5 clearly illustrated in Figs. 1 and 5 of the drawing to permit the entire device to be easily and conveniently supported upon the belt or garment of the sales clerk.

From the foregoing description it will be

- 10 seen that a very simple and efficient holder has been produced which will permit several copies of the sales sheet to be kept and conveniently supported within the body of the holder, and it should be further understood
- 15 that the slips may be easily and conveniently torn from the sales slip without rearranging the sheets of carbon which are adapted to be supported between the several layers of paper.
- 20 It, of course, should be understood that two or more layers of paper may be employed without departing from the spirit of the invention by merely multiplying the number of sheets upon the roll 5. It should
- 25 be further understood that a number of different rolls may be employed in place of the one roll illustrated without departing from the spirit of the invention. In the structure illustrated in Fig. 4 three layers of 30 paper are wound upon the same roll.

Having thus described the invention what is claimed as new, is:—

- 1. A sales slip tablet comprising a body, a cover hinged thereto, a door hinged to the 35 lower edge of said body, said body provided with a pocket upon the lower face thereof adapted to be normally closed by said door, a roll carried by said body, sheets carried by said roll and adapted to pass between the 40 top of said body and the under face of said cover, a pigment interposed between the layers of said sheets, and means for facilitating the tearing of said sheets from said body as said roll is unwound.
- 45 2. A sales slip tablet comprising a body, a cover hinged thereto, a paper roll carried by said body, said roll comprising a plurality of coiled sheets, said sheets adapted to fit between the upper face of said body and the lower face of said cover, said cover provided with a projecting sharpened end to facilitate the tearing of said sheets from said body as said sheets are unwound from said roll, said body provided with a pocket 50 upon the under face thereof, a door hinged to the lower face of said body, springs engaging said door and engaging said body for holding said door in a closed position, and means for holding said cover in a closed 55 position upon said body.
- 60 3. A sales slip tablet comprising a body, a cover hinged thereto, a paper roll carried

by said body, said roll comprising a plurality of coiled sheets, said sheets adapted to fit between the upper face of said body and the lower face of said cover, said cover provided with a projecting sharpened end to facilitate the tearing of said sheets from said body as said sheets are unwound from said roll, said body provided with a pocket 70 upon the under face thereof, a door hinged to the lower face of said body, springs engaging said door and engaging said body for holding said door in a closed position, and spring latches carried by said body and 75 engaging said cover for normally holding said cover in a closed position upon said body.

4. A sales slip tablet comprising a body, a cover hinged thereto, a paper roll carried 80 by said body, said roll comprising a plurality of coiled sheets, said sheets adapted to fit between the upper face of said body and the lower face of said cover, said cover provided with a projecting sharpened end 85 to facilitate the tearing of said sheets from said body as said sheets are unwound from said roll, said body provided with a pocket upon the under face thereof, a door hinged to the lower face of said body, springs engaging said door and engaging said body for holding said door in a closed position, latch springs secured to said body, said latch springs provided with projecting knobs for facilitating the releasing of said 90 springs, said latch springs also provided with projecting tongues, and said cover provided with apertures formed therein for facilitating the receiving of said projecting tongues of said latch springs whereby said 100 cover will be held in a closed position upon said body.

5. A sales slip tablet of the class described comprising a body, a cover hingedly secured thereto, a recording sheet carried by said 105 body and passing between said cover and body, a receptacle formed in the bottom of said body for facilitating the storage of slips torn from said sales slip holder, a hanger secured to said body for facilitating the attachment of said body to a support, a plurality of flanges carried by the upper face of said body, and a record slip engaging the under face of said flanges and adapted to be held in engagement with said body.

In testimony whereof we hereunto affix our signatures in presence of two witnesses.
